US00D851678S

(12) **United States Design Patent** (10) **Patent No.:** **US D851,678 S**
Clymer (45) **Date of Patent:** **** Jun. 18, 2019**

(54) **DISPLAY SCREEN OR PORTION THEREOF WITH GRAPHICAL USER INTERFACE**

(71) Applicant: **Lutron Technology Company LLC**,
Coopersburg, PA (US)

(72) Inventor: **Erica L. Clymer**, Northampton, PA
(US)

(73) Assignee: **Lutron Technology Company LLC**,
Coopersburg, PA (US)

(**) Term: **15 Years**

(21) Appl. No.: **29/629,838**

(22) Filed: **Dec. 15, 2017**

(51) **LOC (11) Cl.** **14-04**

(52) **U.S. Cl.**

USPC **D14/492; D14/485**

(58) **Field of Classification Search**

USPC **D14/485-495**

CLAIM

The ornamental design for a display screen or portion thereof with graphical user interface, as shown and described.

DESCRIPTION

FIG. 1 shows a display screen or portion thereof with graphical user interface showing my new design; and, FIG. 2 shows another embodiment thereof.

The peripheral dashed broken lines illustrate a display screen or portion thereof and form no part of the claimed design.

1 Claim, 1 Drawing Sheet
